SASH CONSTRUCTION

Filed June 18, 1930

UNITED STATES PATENT OFFICE

WILLIAM S. HAMM, OF ELKHART, INDIANA, ASSIGNOR TO THE ADLAKE COMPANY,
OF CHICAGO, ILLINOIS, A CORPORATION OF ILLINOIS

SASH CONSTRUCTION

Application filed June 18, 1930. Serial No. 461,895.

This invention has to do with vertically slidable sash, and is particularly concerned with that type of vertically slidable sash which is closed when in its lowermost position and opens by raising, which type is the one commonly used in the window openings of railway cars and motor busses.

The principal object of the invention is to provide improved means for raising and lowering a sash of the type described, which means includes a novel connection between the sash and the actuating mechanism which is hidden from view in all positions of the sash, does not in any way impair the weatherproofing of the sash or the frame, is inexpensive to manufacture, is easy to install and may be readily detached from the sash to permit removal of the latter.

Other objects and advantages of the invention will be apparent upon a full understanding of the construction, arrangement and operation of the connecting means.

One form of the invention is presented herein for the purpose of exemplification, but it will of course be appreciated that the invention may be embodied in other structurally modified forms coming equally within the scope of the appended claims.

In the accompanying drawings:

Fig. 1 is an inside view of a double window equipped with the sash connection of the invention;

Fig. 2 is a vertical section through one of the window frames shown in Fig. 1;

Fig. 3 is a fragmentary horizontal section, taken on the line 3-3 of Fig. 2;

Fig. 4 is a fragmentary vertical section, taken on approximately the line 4-4 of Fig. 2;

Fig. 5 is a fragmentary horizontal section, taken on the line 5-5 of Fig. 2; and

Fig. 6 is a fragmentary vertical section, taken on the line 6-6 of Fig. 2.

In the particular embodiment of the invention which is shown in the drawings, a vertically slidable sash 10 is positioned in a window frame 11. The sash, when in its lowermost position, completely closes the opening in the frame. The stiles of the sash are arranged in guide grooves 12 which are formed in post plates 13 attached to the op-

posite sides of the frame. The portions of the post plates immediately behind the grooves are spaced a little from the sides of the frame, whereby to provide closed conduits 14 in which two vertical rods 15 are housed. 55

The lower ends of the rods 15 are rigidly secured to the ends of a horizontal cross bar 16 which is located in a deep pocket 17 beneath the sill 18 of the frame, while the upper ends of the rods carry studs 19 which project laterally through vertical slots 20 in the backs of the grooves 12 into sockets 21 in the edges of the stiles of the sash. 60

The lower ends of the slots 20 in the post plates are located some distance above the sill 18, preferably above the center of the sash when the latter is closed, in order that, when the sash is raised as far as it is intended to go, the edges of the stiles of the sash will still completely cover up the slots. It will 70 of course be understood that the length of the slots 20, as well as the clearance in the pocket 17 above the cross bar 16, is sufficient to permit the sash to be raised to its open position. The portions of the rods 15 which extend below the sill 18 travel up and down in grooved guide strips 22 which are attached to the frame work present at the sides of the pocket 17. 75

The studs 19 are normally maintained in 80 the sockets 21 by means of anti-friction rollers 23 which bear against the sides of the frame 11 and are connected to the upper ends of the rods 15 by spring strips 24. The studs 19 may be withdrawn from interlocking engagement with the sockets 21 by forcing the upper ends of the rods 15 away from the stiles of the sash against the yielding resistance offered by the strips 24. This may be conveniently done, after removing certain 90 retaining strips 25 and 26 detachably secured to the post plates, by inserting a pointed tool of some kind in small openings 27 in the post plates at one side of the sash and pressing back the lower laterally extending portions 95 28 of L-shaped spring strips 29 attached to the post plates. The portions 28 of the strips 29 are normally disposed against the inside faces of the post plates between the latter and the rods 15, with the result that, when 100

the portions 28 are forced away from the post plates, they will engage with the rods 15 and will move the latter far enough toward the sides of the frame to disengage the studs 19 5 from the sockets 21, whereupon the sash may be removed.

The cross bar 16 may be raised and lowered by any suitable means, such as a rack 30 which is attached to the cross bar and meshes with 10 a pinion 31. The pinion 31 is journaled in the frame beneath the sill and is rotated by means of a small crank-shaped handle 32. When a pinion and rack arrangement is used, the rack may be jointed in order to fold up 15 into an out-of-the-way position when the sash is raised, and the pinion may be urged to rotate in one direction by a coil spring in order to counterbalance the weight of the sash when the latter is raised. The pinion 20 and rack arrangement above described, which is a well known construction, is merely shown by way of illustration, since it will be obvious that the rods 15 may be raised or lowered by means of many other different 25 instrumentalities without departing from the spirit of the invention.

I claim:

1. In sash construction, a frame, two hollow sash guides attached to the sides of the 30 frame, a sash mounted in the guides for vertical movement, two vertical rods positioned in the hollow portions of the guides, connections between the rods and the sash passing through vertical slots in the upper portions only of the guides, and means for raising and lowering the rods.

2. In sash construction, a frame, two hollow sash guides attached to the sides of the 40 frame, a sash mounted in the guides for vertical movement, two vertical rods positioned in the hollow portions of the guides, connections between the upper ends of the rods and the sash passing through vertical slots in the upper portions only of the guides, and means for 45 raising and lowering the rods.

3. In sash construction, a frame, two hollow sash guides attached to the sides of the 50 frame, a sash mounted in the guides for vertical movement, two vertical rods positioned in the hollow portions of the guides, connections between the upper ends of the rods and the sash passing through vertical slots in the upper portions of the guides, means for releasing said connections to permit removal 55 of the sash from the guides, and means for raising and lowering the rods.

4. In sash construction, a frame, two hollow sash guides attached to the sides of the 60 frame, a sash mounted in the guides for vertical movement, two vertical rods positioned in the hollow portions of the guides, studs projecting laterally from the upper ends of the rods through vertical slots in the guides into sockets formed in the stiles of the sash, 65 and means for raising and lowering the rods.

5. In sash construction, a frame, two hollow sash guides attached to the sides of the frame, a sash mounted in the guides for vertical movement, two vertical rods positioned in the hollow portions of the guides, studs 70 projecting laterally from the upper ends of the rods through vertical slots in the guides into sockets formed in the stiles of the sash, means for springing the rods away from the guides toward the sides of the frame to retract the studs from the sockets, and means for raising and lowering the rods. 75

6. In sash construction, a frame, a vertically movable sash in the frame, a U-shaped yoke positioned about the sash with the sides of the yoke adjacent the sides of the sash and the bottom of the yoke spaced below the bottom of the sash, post plates attached to the sides of the frame between the sides of the sash and the sides of the yoke, connections 80 between the sides of the sash and the sides of the yoke extending through vertically elongated slots in the post plates, and means for raising and lowering the yoke. 85

7. In sash construction, a frame, a vertically movable sash in the frame, a U-shaped yoke positioned about the sash with the sides of the yoke adjacent the sides of the sash and the bottom of the yoke spaced below the bottom of the sash, post plates attached to the sides of the frame between the sides of the sash and the sides of the yoke, laterally separable connections between the sides of the sash and the sides of the yoke extending through vertically elongated slots in the post plates, and means for raising and lowering the yoke. 90

8. In sash construction, a frame, two hollow guides attached to the sides of the frame, a sash mounted in the guides for vertical movement, means housed within the guides for moving the sash, readily separable connections between said means and the sash passing through vertical slots in the guides, and means for operating said sash-moving 100 means. 105

In testimony whereof I have hereunto subscribed my name.

WILLIAM S. HAMM.
